UNITED STATES PATENT OFFICE.

ANDREW H. BAKKEN, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER INTERLOCK.

Application filed May 11, 1921. Serial No. 468,556.

To all whom it may concern:

Be it known that I, ANDREW H. BAKKEN, a citizen of the United States, and a resident of Edgewood Park, in the county of Allegheny and State of Pennsylvania, have invented a new and useful Improvement in Circuit-Interrupter Interlocks, of which the following is a specification.

My invention relates to mechanical interlocking devices that are adapted to insure the proper relative movements of a plurality of levers, such as are employed in connection with the operation of electric switches.

My invention is designed especially for use in connection with electric motors that require a relatively low voltage when being started to bring them up to, and a higher voltage to maintain them at, their normal running speeds.

One object of my invention is to provide a construction wherein the switch that controls the low-voltage circuit must be moved to closed position and then completely opened before the switch that controls the high-voltage circuit can be closed and wherein in each switch is held against closing movement while the other switch is in closed position.

Another object is to provide means whereby the switch that controls the high-voltage circuit cannot be moved to closed position except within a limited time after the low-voltage circuit has been opened.

Various types of apparatus have been designed to automatically provide for the proper sequence of operation, as between a starting switch and a running, or high-voltage, switch, but difficulty has been experienced in designing a structure wherein provision is made to insure the closing of the running switch before the motor has lost the momentum set up therein through the operation of the starting switch.

I provide a construction wherein the running switch must be closed, if at all, at substantially the instant that the starting switch lever reaches its open position, and one wherein the use of springs, with the difficulties incident thereto, are avoided.

In the accompanying drawings:

Figure 1 is a view, in side elevation, of a

circuit breaker having a device embodying my invention applied thereto;

Fig. 2 is a side elevation, partially in section;

Fig. 3 is an elevational view, looking from the right of Figs. 1 and 2;

Fig. 4 is a plan view of the supporting bracket which forms part of my device;

Fig. 5 shows side and front elevational views of a portion of my device;

Fig. 6 comprises views, in side and in front elevation, of another portion of my device, and

Figs. 7 and 8 are views showing the positions occupied by certain of the apparatus at one stage of operation.

The invention is shown as applied to oil circuit breaker 9 of an ordinary type that is provided with a supporting frame 10 and a tank 11.

The operating lever 12 is pivoted to the frame 10 and is connected to a cross-bar lever 13, through a toggle link 14. The cross-bar lever 13 carries a cross-bar 15 which has operating rods 15^a that are arranged to operate the circuit-closing contact members of a low-voltage switch, in the usual manner, to close a low-voltage circuit through a motor (not shown).

In a similar manner, an operating lever 16 is provided for controlling, through a toggle link 17, a cross-bar lever 18, a cross-bar 19 and operating rods 19^a, a high voltage circuit through the motor.

The toggle link 14 is connected to the lever 13 by a pin 20 the ends of which are extended in the manner shown more clearly in Fig. 3, and the toggle lever 17 is connected to the lever 18 by a pin 21 that also has its ends extended as shown in Fig. 3.

A bracket 24, which is secured to the framework 10 by means of a bolt 25, is provided with a pair of projections 26 and 27 through which a pin 28 extends, and is also provided with a pair of ears 29 through which a pin 30 extends.

A latch member 31 is pivotally supported on the pin 30, while a locking lever 32 is pivotally supported by the pin 28. The pin 28 serves also as a pivot for an idler lever 33.

The locking lever 32 is provided with

four depending arms 35, 36, 37 and 38 that are adapted to cooperate with the pins 20 and 21, while the idler lever 33 is provided with a depending arm 39 that is adapted to cooperate with the pin 21, and an arm 40 which serves merely to increase the weight of the idler lever.

When the switch-operating levers 12 and 16 are in neutral position, the pins 20 and 21 are both in the horizontal plane occupied by the pin 21 in Fig. 1, and the locking lever 32 is engaged by the latch 31. This engagement occurs when the locking lever 32 occupies a position intermediate those of Figs. 1 and 7.

When the locking lever 32 is in latched position, the movement of the pin 21 is unobstructed by the arm 36, and the pin 20 is free to be moved upwardly between the arms 37 and 38. However, the depending arm 39 of the idler lever 33 normally blocks the passage of the pin 21 to its upper or closed position.

If now the operating lever 12 be moved to its closed position, as illustrated in Figs. 1 and 3, the pin 20 will trip the latch 31 and permit the locking lever 32 to swing to the position illustrated in Figs. 1 and 2, under the action of gravity. This movement of the locking lever 32 causes the arm 37 to swing into position under the pin 20 (Fig. 2).

If the starting-switch lever 12 be then raised quickly, the pin 20 will descend rapidly to its lower or open position, imparting a cam action to the arm 37 and causing the locking lever 32 to swing to the position illustrated in Figs. 7 and 8. While the locking lever is moving to this position, the pin 21 of the running-switch lever 16 is uncovered by the arm 35, and the pin 21 may be moved to closed position, provided it has, in the meantime, been unlocked from its engagement with the arm 39 of the lever 33.

When the pin 21 has reached its closed position, as indicated in Figs. 7 and 8, the arm 38 of the lever 32 will lie in the path of the pin 20 of the starting-switch lever 12 to prevent movement thereof to closed position and, so long as the running-switch lever remains closed, the starting-switch lever cannot be closed. When the running-switch lever 16 is returned to open position (Fig. 1), the locking lever 32 is returned to locked engagement with the latch 31 and the idler lever 33 again bars the pin 21 against movement to closed position, while the pin 20 of the starting-switch lever has an unobstructed path for movement to its closed position.

Starting with the operating levers 12 and 16 in their uppermost or open positions and the pins 20 and 21, consequently, in their lowermost positions, the operation of the device is as follows:

The operating lever 12 is moved to its

closed position, as illustrated in Figs. 1, 2 and 3, thus bringing the pin 20 into engagement with the latch 31 to trip the same and permitting the locking lever 32 to swing downwardly about the pivot 28.

Meantime, the lever 16 has been depressed to bring the pin 21 into engagement with the arm 39 of the idler lever 33 and pressure is maintained on the lever 16, so that, when the arm 39 shall have been tripped out of engagement with the pin 21, the pin 21 will advance upwardly with a snap movement.

If now the lever 12 be raised quickly, the cam action imparted by the pin 21 to the arm 37 will cause the locking lever 32 to swing slightly past the position shown in Figs. 7 and 8 and, during such swinging movement, the lever 32 will abut against a projection 40' on the idler lever 33 and trip the leg 39 of such lever out of engagement with the pin 21 and as the leg 35 of the locking lever 32 swings clear of the path of the pin 21, the pin 21, being under stress, will snap up into its closed position, as shown in Fig. 7.

Because of the fact that, when in this position, the pin 21 maintains the locking lever 32 in such relation to the pin 20 that the pin is held against upward movement, the starting-switch lever cannot be advanced until the running-switch lever and the pin 21 carried thereby have been returned to neutral position, and it is equally apparent that the running-switch lever cannot be moved to closed position until the starting switch lever has completed a cycle of movement and that, even under that condition, the running-switch lever must be advanced, if at all, before the locking member 32 returned to its normal or locked position, under the action of gravity.

The projection 35 of the locking lever 32 is made wide enough at its lower end to bar advancement of the pin 21 to advanced position, whether the lever 32 occupies the position of Fig. 1, or whether it is in latched engagement with the member 31, but the projection 39 of the idler lever 33 extends slightly farther than does the projection 35, as shown in Fig. 3, and the pin 31 normally co-operates with the projection 33, if desired, the idler lever 33 may be dispensed with, in which case the pin 21 would be normally barred against advancement directly by the projection 35, but the idler lever 33 serves the additional function of so positioning the pin 21 that it may be readily snapped into position when the pin 21 is brought downwardly to release the pin 21. With the lever 33 removed and the pin 21 held in position against the projection 35, the lever 32 would not swing as readily to the position of Figs. 7 and 8, when the pin 20 is swung downwardly.

Various other changes in the details of

construction might be made without avoiding the spirit of the invention, as defined in the accompanying claims.

I claim as my invention:

5. 1. The combination with a starting-switch lever and a running-switch lever, of a sequence interlock comprising a lever pivoted eccentrically of its center of gravity and normally restrained from movement to 10 its lowermost position, a projection on the pivoted lever adapted to bar movement of the running-switch lever to closed position when the said pivoted lever occupies its normal position, a second projection adapted 15 to bar movement of the starting-switch lever when the first-named projection has freed the running-switch lever, and means operated by the starting-switch lever during its cycle of movement for moving the first 20 projection out of the path of the running-switch lever and for moving the second projection into the path of movement of the starting-switch lever.

2. The combination with a starting-switch lever and a running-switch lever, of a sequence interlock comprising a lever pivoted eccentrically of its center of gravity and normally restrained from movement to its lowermost position, a projection on the 25 pivoted lever adapted to bar movement of the running-switch lever to closed position when the said pivoted lever occupies its normal position, a second projection adapted to bar movement of the starting-switch lever when the first-named projection has freed the running-switch lever, and means 30 operated by the starting-switch lever during its movement to open position for moving the first projection out of the path of 35 the running-switch lever.

3. The combination with a starting-switch lever and a running-switch lever, of a pivoted lever normally positioned so that its center of gravity lies in a substantially 45 horizontal direction from its point of pivotal support, means for releasably holding the pivoted lever in its normal position, a projection on the pivoted lever adapted, when in normal position, to bar advancement 50 of the running-switch lever to closed position, a second projection on the said pivoted lever adapted to bar advancement of the starting-switch lever to closed position when the pivoted lever is in released 55 position with respect to the running-switch lever, means actuated by the starting-switch lever during its closing movement for releasing the pivoted lever, and means actuated by the starting-switch lever during its opening movement for moving the pivoted lever to released position and in locked position 60 with respect to the starting-switch lever.

4. The combination with a starting-switch lever and a running-switch lever, of a pivoted lever normally positioned so that

its center of gravity lies in a substantially horizontal direction from its point of pivotal support, means for releasably holding the pivoted lever in its normal position, a projection on the pivoted lever adapted, 70 when in normal position, to bar advancement of the running-switch lever to closed position, a second projection on the said pivoted lever adapted to bar advancement of the starting-switch lever to closed position when the pivoted lever is in released position with respect to the running-switch lever, means actuated by the starting-switch lever during its closing movement for releasing the pivoted lever, a cam member 75 carried by the pivoted lever in position to swing under the starting-switch lever when such lever is being moved to its closed position, means actuated by the starting-switch lever during its closing movement to release the pivoted lever, and a member carried by the starting-switch lever for engaging said cam member to swing the pivoted lever to released position with respect to the running-switch lever and to locked position 80 with respect to the starting-switch lever during a rapid movement of the starting-switch lever to open position.

5. The combination with a starting-switch lever and a running-switch lever, of a pivoted lever normally positioned so that its center of gravity lies in a substantially horizontal direction to its point of pivotal support, means for releasably holding the pivoted lever in its normal position, a projection on the pivoted lever adapted, when in normal position, to bar advancement of the running-switch lever to closed position, a second projection on the said pivoted lever adapted to bar advancement of the starting-switch lever to closed position when the pivoted lever is in released position with respect to the running-switch lever, means actuated by the starting-switch lever, during its closing movement, for releasing the pivoted lever, a cam member carried by the pivoted lever in position to swing under the starting-switch lever when such lever is being moved to its closed position, means actuated by the starting-switch lever during its closing movement to release the pivoted lever, a member carried by the starting-switch lever for engaging said cam member to swing the pivoted lever to released position with respect to the running-switch lever and to locked position with respect to the starting-switch lever during a rapid movement of the starting-switch lever to open position, and means carried by the running-switch lever for maintaining the pivoted lever in locked position with respect to the starting-switch lever during the period that the running-switch lever remains in closed position.

6. The combination with a starting-switch

- lever and a running-switch lever, of a pivoted member adapted, when in normal position, to bar advancement of the running-switch lever to closed position and, when in another position, to bar advancement of the starting-switch lever to closed position, means for releasably maintaining the pivoted member in normal position, means actuated by the starting-switch lever for releasing the pivoted member, and other means actuated thereby for moving said pivoted lever to locked position with respect to the starting-switch lever.
7. The combination with a starting-switch lever and a running-switch lever, of a pivoted member adapted, when in normal position, to bar advancement of the running-switch lever to closed position and, when in another position, bar advancement of the starting-switch lever to closed position, means for releasably maintaining the pivoted member in normal position, means actuated by the starting-switch lever, during its movement to closed position, for releasing the pivoted lever, and other means actuated thereby for moving said pivoted lever to locked position with respect to the starting switch lever.
8. The combination with a starting-switch lever and a running-switch lever, of a pivoted member adapted, when in normal position, to bar advancement of the running-switch lever to closed position and, when in another position, to bar advancement of the starting-switch lever to closed position, means for releasably maintaining the pivoted member in normal position, means actuated by the starting-switch lever, during its movement to closed position, for releasing the pivoted lever, and other means actuated thereby, during its movement to open position, for moving said pivoted lever to locked position with respect to the starting-switch lever.
9. The combination with a starting-switch lever and a running-switch lever, of an eccentrically mounted pivoted member co-operating with the running-switch lever, when the running-switch lever is in closed position, to bar movement of the starting-switch lever to closed position, a positioning member normally in position to be engaged by the running-switch lever to bar

advancement thereof to closed position, a projection on the pivoted member normally lying in the path of movement of the running-switch lever, a second projection provided with a cam surface adapted to be engaged by the starting-switch lever during a portion of its movement to open position to cause the pivoted member to swing about its pivot and carry the first named projection out of the path of the running-switch lever, and means whereby the said movement of the pivoted member causes disengagement of the positioning member and the running-switch lever to permit the advancement of said lever to closed position.

10. The combination with two reciprocably movable switch members, of means for preventing the advancement of one member except at substantially the instant that the other member has reached a retracting position.

11. The combination with a starting-switch lever and a running-switch lever, of a pivoted member co-operating with the running-switch lever, when the running-switch lever is in closed position, to bar movement of the starting-switch lever to closed position, a second pivoted member normally in position to bar advancement of the running-switch lever to closed position, and means actuated by the starting-switch lever, during its movement to open position, to move the second-named pivoted member out of the path of movement of the running-switch lever.

12. The combination with a starting-switch lever and a running-switch lever, of a pivoted member co-operating with the running-switch lever, when the running-switch lever is in closed position, to bar movement of the starting-switch lever to a closed position, a second pivoted member normally in position to bar advancement of the running-switch lever to closed position, and means actuated by the starting-switch lever at the completion of a cycle of movement thereof to move the second pivoted member and permit advancement of the running-switch lever to closed position.

In testimony whereof, I have hereunto subscribed my name this 28th day of April 1921.

ANDREW H. BAKKEN.
